[57] CLAIM

The ornamental design for a compact, as shown and described.

DESCRIPTION

FIG. 1 is a top front perspective view of a compact showing my new design;

FIG. 2 is a left side elevational view thereof in open position;

FIG. 3 is a back top perspective view thereof in an open position; and

FIG. 4 is a top front perspective view in the open position.

The top and bottom faces are of identical configuration.
